CLAIM

The ornamental design for a cap of packaging container as shown and described.

DESCRIPTION

FIG. 1 is a perspective view of a cap of packaging container, showing our new design.

FIG. 2 is a front view thereof.

FIG. 3 is a top plan view thereof.

FIG. 4 is a bottom plan view thereof.

FIG. 5 is a right side view thereof; and,

FIG. 6 is a sectional view taken along line 6-6 of FIG. 2. The broken lines in the figures illustrate the portions of the cap of packaging container that form no part of the claimed design. The thin line of the perspective view indicates the three-dimensional surface of the product. A rear view is omitted because it appears same with the front view. A left side view is omitted because it appears same with the right side view.
